UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

MUSICAL-INSTRUMENT PLAYER.

1,172,805.

Specification of Letters Patent. Patented Feb. 22, 1916.

Application filed November 18, 1905. Serial No. 287,989.

To all whom it may concern:

Be it known that I, PAUL BROWN KLUGH, a citizen of the United States, residing at Chicago, in the county of Cook and State of Illinois, have invented certain new and useful Improvements in Musical-Instrument Players, of which the following is a specification.

My invention relates to attachments for mechanically operating pianos or similar musical instruments without interfering with their capacity for manual playing.

The primary object of the invention is to provide a device of this character, which may be readily fitted and attached within the case of an instrument of this class and as readily removed therefrom, which is simple and economical in construction, with delicate and responsive means, under control of the operator, for accenting particular passages of the music, changing tempo or tone volume, repeating, accelerating, retarding or holding parts and producing crescendo or diminuendo effects according to the taste of the player or directions upon the perforated sheet.

The invention also provides means for promptly venting the sounding mechanism on rewind, high and low pneumatic tension from the same exhaust bellows chest through to the sheet-propelling motor and pneumatic actions and effective and responsive dynamic control.

Further objects will be more particularly described in the specification and pointed out in the claims.

In the accompanying drawings, I have shown a standard size piano embodying my invention in one of its preferred forms. Figure 1 is a front view with the upper and lower front boards or panels removed to reveal the interior construction. Fig. 2 is an enlarged broken vertical sectional view taken on line 2 of Fig. 1 looking in the direction of the arrow. Fig. 3 is a plan sectional view on line 3 of Fig. 1 looking in the direction of the arrow. Fig. 4 is an enlarged broken sectional plan view taken on line 4 of Fig. 1. Fig. 5 is a perspective diagrammatic view of the rewind, tempo, modulating and sustaining levers with their connections to the respective operated parts. Fig. 6 is an enlarged broken sectional elevation of one of the bellows sections, one of the governors and a valve chamber *c*, taken

on line 6 of Fig. 3. Fig. 7 is a plan sectional view of this valve chamber taken on line 7 of Fig. 6. Fig. 8 is an enlarged broken sectional elevation of the right hand bellows section, one of the governors and the valve chamber *c'*, taken on line 8 of Fig. 3. Fig. 9 is a plan sectional view of this valve chamber, taken on line 9 of Fig. 8 looking in the direction of the arrow. Fig. 10 is a vertical sectional view taken on line 10 of Fig. 12, showing one of the upper pneumatic actions in sectional elevation and one of the lower pneumatic actions in side elevation and illustrating the operative connections of one of the piano abstracts. Fig. 11 is an enlarged sectional view through the venting box and chamber, taken on line 11 of Fig. 12, showing means for venting one of the tracker tubes. Fig. 12 is a sectional broken diagrammatic view showing the pneumatic actions, a motor governor, sheet shifting pneumatics, the pneumatic for operating the reversing mechanism to wind and rewind the sheet, the trackerboard, the venting chamber and their respective connections. Fig. 12² is a broken face view of a portion of the tracker-board showing some of the tracker orifices and trigger openings for inaugurating the operation of the shifting mechanism. Fig. 13 is a plan view of the upper crank for moving the locking bar under the manual keys. Fig. 14 is a plan sectional view of the lower crank adapted to turn the shaft upon which is mounted the crank shown in Fig. 13. This view is taken on line 14 of Fig. 15. Fig. 15 is a broken sectional view, taken on line 15 of Fig. 13, representing the connections and mechanism employed for operating the hinged locking bar under the manual keys. Fig. 16 is a sectional elevation of portions of the sheet winding, shifting and reversing mechanisms. Fig. 17 is a front view of the mechanism, shown in Fig. 16. Fig. 18 is a broken sectional view showing the means for removably supporting one end of the music or rewinding roll, taken on line 18 of Fig. 16.

For convenience in understanding the relative disposition of the parts of my attachment, I have shown an upright piano of standard size and of ordinary construction, wherein A is the case, B the upper front board, C the lower front board, D the fall-board, E the sliding trackerboard panel, F

the strings, G the piano action, H the piano abstract, J the action rail, K the piano keys, L the key-bed, M the key slip, N the sounding board, O the back uprights, P the head block and Q the piano string frame.

It is, however, obvious that many modifications in the size, arrangement, connections and disposition of the parts of my device, depending to some extent upon the 10 style and size of the instrument in which it is to be placed, may be made without departing from the principles of my invention.

Within the lower portion of the piano case, below the key-bed, I provide means for 15 detachably securing the bellows mechanism, which in this class of mechanical players usually comprises a chest, reservoirs, ports and pumps operated by pedal connections adapted to create pneumatic tension within 20 the chest, the latter communicating through various windways, having valves under control of the operator or the music sheet with the player parts which throw the piano hammers and propel and guide the music sheet.

My preferred form of sectional bellows construction is made the subject of a co-pending application, issued as Patent No. 914,351, of March 2, 1909, and I will but 30 briefly describe it, it being understood that my construction of the bellows chest in separately removable sections or divisions facilitates attachment and detachment thereof within the instrument case and that variation in the sectional construction and arrangement may be made.

Near the middle of the piano, I provide 40 an upright support 1, having two vertically disposed straps 3 and 3^a countersunk in the rear surface and bent over the top at right angles so that they may be screwed, or otherwise fastened, to the key-bed at 2, the support 1 being similarly secured at the lower end to the string frame Q of the piano. 45 (See Fig. 1.) To the opposite interior ends of the piano case are secured a pair of upright cleats 5 and 5^a on the left hand and 6 and 6^a on the right, both pairs tapering inwardly so as to form oppositely disposed recesses or sockets 7 and 7^a. The cleats on the same side of the case are far enough apart to permit the outer ends of the bellows chest sections to fit snugly between them. Rigidly secured to the up- 55 right 1, or made integral with it, is a vertical wedge-block or tongue 4, tapering outwardly and of sufficient size to fill the intervening space between adjacent ends of the sections when they are set in place.

60 I provide a bellows chest composed of a plurality of separately removable sections or divisions. In the drawings I have shown two sections or divisions separately placed or attached so they may be taken out one 65 at a time, having the usual tension creat-

ing and retaining mechanism comprising pumpers 8 and 8^a, pedals 9 and 9^a, reservoirs 10 and 10^a and chests 11 and 11^a. The sections are set in the instrument by thrusting the outer ends into the sockets 7 70 and 7^a, and pressing the inner ends against the sides of the wedge-member 4, in which position they may be detachably fastened by bolts 13, suitably threaded and provided with nuts. In order that the pneumatic 75 tension may be the same within the sections, I cut openings therein and fit the ends of windway connections 12 and 12^a thereto. The configuration of the sections is such that ready access may be had to the string 80 frame through the opening 15.

Mounted on the left hand section is a valve chamber c and a tension regulator or governor d, while similarly mounted on the right hand section is a valve chamber c' and a similar governor d'. Chests 11 and 11^a communicate with chambers c and c' respectively through passages provided with valves and rod connections under control of the operator. I prefer to use a governor 85 comprising an expansible air chamber, to a movable member of which is attached a ball valve d⁴, normally held from its seat in the passage to the chest by spring d², and adapted automatically to diminish or increase 90 the opening therein in accordance with the increase or decrease of the pneumatic tension in the chamber. Valve chamber c is provided with high tension direct and low tension indirect communications to chest 11, the direct communication being through 95 passage 19 and the indirect communication through opening 18, channel 16, opening 17, governor d and opening 20. Channel 16 is preferably disposed within the top of the 100 chest 11. The opening 19 may be opened and closed independently of, or simultaneously with, opening 18 by valves controlled by the modulating and rewind levers. 105

From valve chamber c lead the windways 110 through which pneumatic tension is communicated to the mechanism for actuating the piano hammers and for shifting the connections to apply alternately the power of the motor for advancing and rewinding the 115 music sheet. I prefer to detachably couple these windways to the chamber c by capping the latter with a face plate having a tubular opening 22 to which a pipe 23 leads from the chambers 81 of the pneumatic actions 24. Valve chamber c' is similarly provided with high tension direct and low tension indirect communications to chest 11^a controlled by independent valves operated by the rewind and tempo levers. A channel 120 25 within the top of chest 11^a communicates with governor d' through opening 26 and with valve chamber c' through opening 27. The valve chamber c' communicates directly with chest 11^a through passage 28 125 130

and indirectly through opening 27, channel 25, opening 26, governor d' , and opening 29. A pipe coupling 30 on chamber c' is provided with a flexible pipe 31 bringing 5 this chamber into communication with the motor which operates the sheet propelling mechanism.

The levers by which the various parts of my device are preferably controlled are four 10 in number and are conveniently arranged below the keys and provided with handles and a finger rest on the front of the instrument. I prefer to construct this rest by merely cutting away or recessing the key-slip M 15 and providing four slots therein, each adapted to permit lateral movement of the lever extending therethrough. The bottom of this recess m affords a rest for the fingers.

Tempo-lever 33 extends backward in a 20 horizontal plane through its slot in recess m and is pivoted at 36 to the key-bed L . To the rear or inner end of this lever is attached an end of connecting rod 37, the other end of which is secured to valve-stem 25 38 on valve 39 in chamber c' . This valve controls opening 27 between chamber c' and governor d' . Near the forward end of lever 33 is fastened one end of a link connection 40, the other end being attached to an arm 20 of a double crank 41, the other crank-arm being connected to the lower end of a swinging arm 42 pivotally secured at 43 by bracket 44 attached to case A. To the upper end of this swinging arm 42 is adjustably secured a rod 45 leading to a tempo 35 indicator or scale 48. Rod 45 is provided with a double eye or universal joint 46, and an indicating finger 47 adapted to travel along the scale 48.

Modulating-lever 34 extends backward in a horizontal plane through its slot in recess m and is pivoted to the key-bed at 49. To the rear end of this lever is attached one 40 end of link 50, the other end being adjustably secured to valve-rod 51 provided with collar 52 within the valve chamber c . Valve-rod 51 passes through ear 55 projecting upwardly from valve 53. Collar 52, impinging against ear 55, closes the valve 50 53 over opening 19. This valve is opened by spring 54 within chamber c , one end of which is attached to the wall of the chamber and the other to the ear 55 on the side adjacent to the collar. When lever 34 is drawn to the left by the operator the valve 53 closes the direct opening 19 between chest 11 and chamber c . To return lever 34 to its initial position upon release by the operator a spring 56 is provided attached to 55 the piano case at 57 and to the link 50. By operating lever 34, the direct passage between chamber c and chest 11 is closed, thereby bringing a low tension to bear in the action pneumatics. When the valve 60 controlling this direct passage is open, high

tension is created in the chamber, so as to give the most powerful action upon the striking mechanism, while when this valve is closed communication is had only by an indirect passage through the governor. 70

Sustaining-lever 35 extends backward in a horizontal plane through its slot in recess m and is pivoted to the key-bed L near its rear or inner end at 58. To this rear end is attached one end of a link 59, the other end thereof being connected with one member of a bell-crank 60, pivoted at 61, the other member engaging the upright rod 62 leading from the sustaining pedal of the piano. This rod 62 connects the sustaining 75 pedal for operating the usual piano mechanism for removing the dampers from the strings.

Rewinding-lever 32 extends backward in a horizontal plane through its slot in recess m 80 and is pivoted near its center at 63 to key-bed L . Secured to the rear or inner end of the lever is a link connection 64, the right hand end of which is coupled to valve-stem 65 on valve 66 in chamber c' , over opening 28 while the left hand end is coupled to valve-stem 67 on valve 68 in chamber c over opening 18. For the purpose of affording an adjustable connection of valve-stem 67 on valve 68, I provide a collar 69 adjustably 85 secured by a set screw 70^a to said valve-stem, which, in turn, is confined between two upwardly extending ears or flanges 70 of the valve. Valve-stem 67 passes through ear 55 on valve 53 and extends through a bearing in the end of chamber c . Surrounding the valve-stem 67 and adjacent to ear 55 on the left hand side, as shown in Figs. 6 and 7, is an adjustably secured collar 71. Connected to valve-stem 67 on the outside of the 90 right hand end of chamber c is a valve rod 72, adjustably connected to valve 73, and adapted to open and close a vent or opening 74 between valve chamber c and the outside air. This valve is confined within the guide 95 100 75. When lever 32 is thrown to the left from the position it normally occupies and as shown in Fig. 1, the valves 53 and 68 in the valve chamber c are closed while valve 66 in valve chamber c' is opened. This movement also opens the valve 73, uncovering opening 74 in chamber c , which instantaneously allows outside air to enter and relieves tension upon the action pneumatics and by means of the conduits 127, 199 and 198 upon the bellows 153. The removal of this tension permits expansion of the bellows referred to, thereby shifting the mechanism through which the rolls are operated 110 into position for rewinding the music. At the same time high tension is applied to the motor for operation at the maximum speed. 115

Above the keys and directly back of the 120 front key-board casing are mounted the ac- 125 130

tion pneumatics detachably secured to the case A by plates 76 as shown in Fig. 12. In constructing the pneumatics, I prefer to form two cross-pieces 77 and 77, one mounted above the other and both joined at the opposite ends by blocks 78 having connecting wind passages. Each of these cross-pieces is formed of an upper and lower member 79 and 80, respectively. Upon each of the upper members 79, I mount a row of action pneumatics, these being so arranged and of such size and shape as to allow one row to be placed over the other and each pneumatic directly above one of the keys of the instrument. Each pneumatic 83 is provided with an opening 84, registering with an opening 85, communicating with passage 86, within member 79. Within each of the passages 86 to the rear thereof, is a thimble extension 87 affording communication between passage 86 and chamber 81. Beneath extension 87, and in line therewith, is placed a flexible diaphragm 88 covering opening 89 leading from chamber 81. To the rear of each member 80 of the cross-pieces 77, is a row of thimbles 90 each of which connects with a passage 91 leading from the under side of one of the diaphragms 88. Loosely attached upon each diaphragm, is a disk 92 with stem 93, passing through guides 94 and carrying a valve 95, adapted to alternately open and close the opening to thimble 87 and the opening 96 to the outside air. Valve 95 is secured to stem 93, by means of washers 97 held in place by elastic or accommodating stops 98. From each nipple 90 and detachably coupled thereto are the lower sections 99 of the tracker tubes.

I prefer to apply the power of the action pneumatics to the piano action by substantially the same means as those shown in my co-pending application issued as Patent No. 833,060 of October 9th, 1906. The movable members 100 of pneumatics 83 are provided with projections 101 through which pass stems 102, which are provided with nuts 103. Yielding washers 104 are placed between the nuts and the projections 101. Each stem is pivoted at its upper end 105 to the outer end of a horizontally disposed lever 106, pivoted at 107 within a bearing strip 108. The rear end of the lever is rounded and cushioned to contact when the pneumatic is collapsed with the under side of a spoon 109 projecting forward from the piano abstract H. It may be found convenient to provide an adjustable bumper 110 above each lever held in position by cross piece 111. By this attachment between the mechanical or pneumatic action and the piano action there is no interference with manual playing. To cross pieces 111 is removably secured an upright frame 112, to which is detachably secured venting chamber 114. The box 113 comprises a rear wall 115, the top and bottom flanges 116, provided with recesses 117, within which is placed glass or transparent sections fitted in gaskets 119 and clamped in place by buttons 120, pivoted at 121 to flanges 116. Within wall 115 are cut a series of vertical holes 122, provided at the top and bottom with nipples 123. To the lower end of each lower nipple is attached one of the lower tracker tube sections 99, and likewise to the upper end of each upper nipple 75 is similarly attached one of the upper sections 99^a. The latter lead to nipples 124 on the rear of the tracker-board f to which they are secured. The tracker-tubes are pneumatically exhausted through pin holes 30 125 in disks 126, leading to venting chamber 114, said chamber communicating with the right hand end of the upper cross piece chamber 81 through pipe connections 127. A slight tension is thus created in the 85 tracker tubes sufficient when the tubes are closed by the sheet to prevent operation of valves 95, but not sufficient to exhaust them, or any one of them when uncovered by the sheet. This tends to hold the sheet and 90 tracker board in close contact.

The motor or wind engine, the tracker board, rewind and take-up rolls, the sheet guiding devices for correcting registration, the shiftable connections for alternately 95 coupling the motor to advance the rolls and thereafter shift them to reverse the rolls, and the pneumatically controlled mechanism for obtaining this reversal, I prefer to mount near the top of the case. This may be 100 conveniently done by providing a rectangular frame g detachably secured to the back of the piano, having a base g' extending out to the right hand side of case A. The 105 tracker board is mounted in the usual manner within the frame g and leading from it are curved rear sections 128, forming recesses for the music or rewinding roll h, and the winding or take up roll i which are journaled in the frame g. The arrangement of 110 the motor or wind engine, the tracker board, the rewind and take up rolls and the connections for alternately coupling the motor to advance and reverse the rolls, may be of any convenient construction. I prefer, however, to arrange them as shown in the drawings. At the right hand end of frame g is 115 mounted a shaft 129, having a slotted socket or head 130 within the frame adapted to receive the usual gudgeon of the music roll, 120 the pin 131 of which engages the slot in head 130. Outside the rectangular frame a disk 129^a is keyed to shaft 129. Bearing against this disk is a spring brake or tension member 129^b adapted to increase tension 125 on the sheet.

In line with shaft 129 at the opposite side of the rectangular frame g is a spring pressed socket 132 normally held against the gudgeon of the music roll by spring 133 130

(Fig. 1). The above described mechanism affords means for inserting music rolls of uniform standard length and for taking them out again when rewound. Take up 5 roll *i* is mounted on shaft 134, having bearings within the frame *g*. This shaft extends beyond the frame on the right hand side as shown in Fig. 17, being preferably pointed at this end and bearing against 10 spring 135^a which tends to thrust the roll to the left. Rigidly mounted on shaft 134 is gear 134^a adjacent to the rectangular frame. Adjacent to shaft 134 is placed a shaft 135, suitably supported in bearings, and provided 15 with a loose sprocket 136 held against lateral movement thereon by an arm 137 which enters a groove in the hub portion of the sprocket. On the left hand face of sprocket 136 is mounted a contact roll 138. 20 Between the sprocket 136 and the rectangular frame *g*, shaft 135 is provided with a pinion 139, having a head 140 carrying on its right hand face pins 141 adapted to engage contact roll 138 on sprocket 136, 25 when thrown to the right to occupy the position shown in Fig. 17. Head 140 is pinned to shaft 135 and provided with an annular groove 142 adapted to engage an upwardly extending finger 143, mounted on shaft 144 30 directly beneath shaft 135 and parallel thereto.

Upon the base extension *g'* of the rectangular frame *g* are uprights 145 supporting a suitable wind motor *j*. This motor being well known in the art is not more particularly described. It is here shown as operated from the flexible windway or pipe connection 31. The motor crank shaft 146 has bearings in both the uprights 145 and is 35 in axial alignment with shaft 135. At its left hand end shaft 146 is provided with a disk 147 pinned thereto. Extending out from this disk is a pin 148 adapted to engage at all times anti-friction roller 149 40 fastened on the end of shaft 135. Upon shaft 129 is mounted a sprocket 150. A sprocket chain 151 passes around sprockets 150 and 136. Intermediate the two sprockets is a belt tightener 152 made adjustable 45 in the usual manner to vary the tension of the sprocket chain.

While I have in the foregoing described a convenient form of shiftable coupling mechanism for alternately operatively uniting the motor and rolls so as to advance the latter and thereafter operatively uniting them so as to reverse this movement, the invention is not limited to the particular construction as shown but contemplates the use 55 of any mechanism which may be coupled to successively operate in directions determined by a shifting device controlled pneumatically from the windways. I prefer to accomplish this object by providing a pneumatic 153 mounted upon the base extension 60

g', its movable member having an arm or link 154 attached to one arm of the bell crank 155, the other arm having pivoted thereto an end of link 156, which in turn is pivoted at the opposite end to shaft 144. It 70 will be seen by reference to Figs. 12 and 17 that shaft 144 will be forced to the left by collapse and to the right by inflation of pneumatic 153. This shaft carries finger 143, which engages groove 142 in the head 75 of pinion 139 and thereby causes pins 141 to engage contact roll 138 when thrust in one direction or it throws pinion 139 into mesh with the gear 134^a when thrust in the opposite direction. Pneumatic 153 is provided 80 through conduits 198, 199 and 127 with operating tension from the air chamber of the pneumatic action 24, and its collapse is dependent upon the presence of operating tension therein. Upon removal of 85 this tension from the pneumatic action, pneumatic 153 returns to normal or inflated position by the action of spring 157, one end of which is secured to one of the uprights 145, and the other to finger 143. Behind 90 shafts 129 and 134 is suitably mounted an oblique upright shaft 158. At its upper end this shaft carries an arm 159 in alignment with the axis of the shaft 129, bearing against the hub of sprocket 150, while near 95 its lower end it carries a similar arm 160 in alignment with the axis of shaft 134 bearing against collar 161 attached to shaft 134. Shaft 158 is provided with a crank 162 connecting with a shifting rod 163, operated by 100 pneumatics hereinafter described.

The tracker-board has the usual orifices *f'*, each communicating with one of the upper sections 99^a of the tracker tubes above described. *k* indicates the music sheet and *k'* 105 the perforations thereon adapted to operate the action pneumatics in proper sequence for playing a tune. Adjacent to these orifices, but out of alignment therewith, are pairs of slits or mouth pieces *f*² and *f*³ arranged alternately across the tracker-board. From each of the orifices *f*² is a pneumatic connection to a pipe *f*⁴ and similarly from *f*³ is a pneumatic connection to a pipe *f*⁵. 110 From pipe *f*⁴ leads pipe 164 and from *f*⁵ leads pipe 165 to the pneumatics *l*² *l*³, respectively. (Fig. 12). These pneumatics may be constructed, operated and controlled as to their operation by the pipes 164 and 165 in any ordinary or desirable manner, but I 115 prefer in this instance the construction shown in Fig. 12 and in the patent granted in part to me October 6, 1906, and numbered 832,982. In the figure referred to *l* represents a central section or valve-chamber having single pneumatics *l*² *l*³ attached on opposite sides. The movable members of the pneumatics are each provided with a bifurcated finger extension 191 embracing shifting rod 163 and adapted to contact with 120 125

collars 194 upon said rod. Upon the central section l is an extension affording a support for the rod 163, and adjacent to this support, upon either side thereof, is a collar 193 adjustably secured to the rod to limit its lateral movement as it is thrust in either direction by the collapse of the pneumatics l^2 l^3 . Operating tension is applied through the conduit or pipe 197.

10 When the music sheet is in normal position, the perforations registering properly with the tracker-board orifices f' the slits or mouth pieces f^2 and f^3 will be covered with the sheet. Should the sheet, however, 15 become abnormally shifted to the left, it will uncover one or more of the slits f^2 allowing air to enter tube 164, operate valve 174 and cause collapse of pneumatic l^2 . The collapse of pneumatic l^2 will shift or slide 20 the rod 163 to the right by bringing bifurcated finger 191 in contact with collar 194. This shifting causes shaft 158 to oscillate and turn arm 160, bearing against collar 161, to thrust shaft 134 of the take-up roll 25 to the right, thus causing the roll to shift the sheet to the right and cover the orifices f^2 thereby bringing about proper registration of the perforations and tracker-board orifices. It being desirable that both rolls 30 shall move simultaneously, it will be seen by inspection of the drawings that upon oscillation of shaft 158, as above described, arm 159 will draw away from the hub extension of sprocket 150 on shaft 129 and 35 simultaneously the tension of spring 133 will shift the music-roll h into contact with the arm 159. When, however, the perforated sheet becomes abnormally shifted to the right it will uncover one or more of the slits f^3 , 40 allowing air to enter the tube or pipe 165 and pass into a corresponding system of passages and valves, and cause collapse of pneumatic l^3 . This causes the bifurcated finger on the pneumatic l^3 to contact with 45 a collar and oscillate shaft 158 in the reverse direction from that caused by the collapse of pneumatic l^2 . The arm 159 will thus be thrust against the collar on shaft 129 against the yielding spring 133 and the 50 spring 135^a will cause shaft 134 to follow up the arm 160, thus shifting the music-sheet to the left to cover the orifices f^3 , and bring about proper registration. Also mounted on the base extension g' of frame 55 g is a governor d^3 conveniently disposed beneath the motor. From pneumatic 153 is a flexible tubular connection 198 which leads to the governor d^3 to which is also connected the flexible pipe 197, leading 60 from the pneumatics l^2 , l^3 (Fig. 12). On the opposite side of governor d^3 is attached a flexible tube 199 leading to a branch of a pipe 127. In this manner governed tension only is applied to the pneumatics l^2

and l^3 and reversing pneumatic 153. Governor d^3 is similar in construction to governors d and d' , heretofore described. Its adjustable valve d^4 is set to permit only a slight suction on pneumatic 153 and pneumatics l^2 and l^3 , thereby preventing the latter from throwing the sheet too far when correcting registration and causing the former to operate alike at all times. It is evident that while governor d^3 delivers operating tension to pneumatics l^2 , and l^3 and 70 153, it in turn receives power from pneumatic action 24 through conduits 199 and 127. When, therefore, tension is admitted to the pneumatic action, all the devices concerned in the forward or playing movement 75 of the music sheet are thereby rendered ready for operation, and upon withdrawal of this tension from the action the devices controlled from the tracker are rendered 80 inoperative and the reversal of the sheet- 85 propelling mechanism is permitted.

As shown in Fig. 2, I hinge or otherwise pivotally secure to key-bed L beneath the manual keys K' at the points n' , a bar n shown in its lowered position in this figure. 90 This bar is adapted to be rocked so as to contact with the under surfaces of the manual keys, thereby affording a rest for them and locking them against movement. To throw the bar n into this position, I attach to the same a bracket n^2 to which is connected one end of a link n^3 (Figs. 13 and 15), its other end being attached to a crank n^4 on a vertical shaft n^5 extending through the key-bed L. Beneath the key-bed this shaft is provided with a similar crank-arm o , normally held in the position shown in Figs. 14 and 15 by a spring o' . A pin or finger-grasp o^2 is provided on the under side of this arm, for the purpose of 95 turning the shaft n^5 and locking the same when the bar is raised in contact with the keys to occupy the position represented by dotted lines in Fig. 15 by means of the spring o^3 attached to the outer side of key-bed L. For the purpose of limiting the throw of the arm o and thereby of bar n , I provide on the outer side of the key-bed L stops o^4 .

Having thus described my invention, 115 what I claim as new and desire to secure by Letters Patent, is:

1. In mechanism for mechanically playing a musical instrument, action pneumatics, sheet-propelling mechanism, a chest provided with wind-supplying apparatus and composed of a plurality of separately removable sections, means for removably securing the separate sections of said chest, disconnectible or severable means pneumatically connecting the sections of said chest, and detachable windways between said action pneumatics and one of the sections of

said chest and between said sheet-propelling mechanism and another of the sections thereof.

2. In mechanism for mechanically playing a musical instrument, a casing, action-pneumatics and a windway communicating therewith supported within said casing, a chest provided with wind-supplying apparatus and composed of a plurality of separately removable sections removable secured within said casing, disconnectible or severable means pneumatically connecting the sections of said chest, and a valve-box associated with one of the sections of said chest and removable therewith, said valve-box being in detachable communication with said pneumatics through said windway.

3. In mechanism for mechanically playing a musical instrument, a casing, a chest, pump-bellows and reservoir-bellows separately secured to said chest; said chest being supported within said casing and said pump and reservoir bellows being collectively disposed upon the outer front of said chest.

4. In mechanism for mechanically playing a musical instrument, sheet-propelling mechanism, action-pneumatics, a chest provided with wind-supplying apparatus and composed of a plurality of separately removable sections, supports for the sections of said chest, disconnectible or severable means pneumatically connecting the sections of said chest, pump-bellows and bellows-pedal connections secured to and collectively disposed upon the outer front of said chest, and windways from said mechanism and pneumatics detachably connected with said chest.

40 5. In mechanism for mechanically playing a musical instrument, a casing, sheet-propelling mechanism and a windway communicating therewith supported within said casing, a chest provided with wind supplying apparatus and composed of a plurality of separately removable sections removably secured within said casing, disconnectible or severable means pneumatically connecting the sections of said chest, and a valve-box associated with one of the sections of said chest and removable therewith, said valve-box being in detachable communication with said mechanism through said windway.

6. In mechanism for mechanically playing a musical instrument, the combination with a bellows-chest, action-pneumatics, sheet-propelling mechanism, windways between said pneumatics and chest and between said mechanism and chest, and valves for controlling said windways, of means operable simultaneously with said valves to correct the degree of air-pressure extending to said pneumatics, when said valves are adjusted to interrupt communication of said

pneumatics with said chest through certain 65 of said windways and establish communication of said mechanism with said chest through other of said windways.

7. In a mechanical musical instrument, in combination with an exhaust chest and 70 means for creating pneumatic tension therein, two valve chambers, each having a direct and indirect communication with said chest, means for automatically limiting the pneumatic tension in said indirect communications, valves in each of said communications, 75 a vent from one of said chambers to the outside air, a valve adapted to open and close said vent, and rewind lever connections adapted to open said vent valve and close 80 said communications between that chamber and the chest and simultaneously open the direct communication between said chest and the other valve chamber, for the purposes described.

8. In a mechanical musical instrument, in combination with an exhaust-chest and means for creating pneumatic tension therein, an air-chamber, direct and indirect passages connecting said chest and chamber, a 90 separate valve for each passage, a governor adapted to limit tension in said indirect passage, a venting orifice from said passages to the outside air, a valve therein, a spring and modulating lever connections adapted alternately to open and close the valve in the direct passage and rewind lever connections adapted alternately to close the valves in said direct and indirect passages and open the venting orifice to outside air and to open 100 the valves in said direct and indirect passages and close the venting orifice.

9. In mechanism for mechanically playing a musical instrument, the combination of a pneumatic power device, action pneumatics, pneumatically operated sheet propelling mechanism, action windways from said power device to said action pneumatics, motor windways from said power device to said propelling mechanism, and 105 means adapted alternately to apply tension and in the motor windways immediately modify tension and admit outside air in the action windways and to modify tension in the motor windways and exclude outside air 110 115 and apply tension in the action windways.

10. In combination with action pneumatics an exhaust device connected by windways to said action pneumatics, valves provided with lever connections adapted alternately to close said windways and admit outside air therein and to open said windways and exclude outside air therefrom.

11. In combination with action windways, exhaust devices adapted to create pneumatic 125 tension therein, a pneumatic provided with a shifting finger, means adapted to alternately apply and withdraw tension to operate said

- pneumatic to move said finger in reverse direction, said means including a vent from said windways to outside air, having a valve provided with lever connections adapted alternately to open said vent and relieve tension in said windways, and to close said vent and exclude outside air therefrom, said valve and said means being connected to operate simultaneously.
12. In combination with a piano, action pneumatics detachably secured therein above the manual keys and adjacent to the abstracts, a bellows chest composed of a plurality of separately removable sections having mechanism adapted to exhaust the air therein, detachable air passages between the removable sections of said chest and between one of the removable sections and said pneumatics and means for detachably securing said sections in the lower portions of the piano.
13. The combination of action pneumatics, exhaust devices adapted to create pneumatic tension, action windways connecting said exhaust devices and said action pneumatics, movable mechanism, and a shifting pneumatic communicating with said action windways adapted to shift said movable mechanism in reverse directions on alternate application and withdrawal of tension in said windways and means for applying and withdrawing tension from said windways.
14. In a mechanism for mechanically playing a musical instrument, the combination of wind devices, action pneumatics, pneumatically operated sheet-propelling mechanism, action windways from said wind devices to said action pneumatics, motor windways from said wind devices to said propelling mechanism, and means adapted upon motion thereof in one direction to apply sufficient tension in the motor windways to operate said propelling mechanism and cut off tension and admit outside air in the action windways and upon motion thereof in the other direction to modify tension in the motor windways and exclude outside air and apply tension in the action windways.
15. In combination with an exhaust device, a motor and action pneumatics, motor windways and action windways, a shifting device operated through said action windways, and means for cutting off pneumatic tension in said motor windways and immediately applying it sufficiently in said action windways to operate said shifting device, said means being adapted on reverse movement to relieve tension in said action windways to cause said device to operate in reverse direction and immediately apply tension sufficiently in said motor windways to operate said motor.
16. In mechanism for mechanically playing a musical instrument, action pneumatics, sheet-propelling mechanism, a chest com-
- posed of a plurality of separately removable sections, means for removably securing the separate sections of said chest, disconnectible or severable means pneumatically connecting the sections of said chest, a valve-box associated with one of the sections of said chest and removable therewith, a detachable windway between said action pneumatics and said valve-box, a second valve-box associated with another of the sections of said chest and removable therewith, and a second detachable windway between the sheet-propelling mechanism and said second valve-box.
17. In mechanism for mechanically playing a musical instrument, action pneumatics, sheet-propelling mechanism, a chest composed of a plurality of separately removable sections, means for removably securing the separate sections of said chest, disconnectible or severable means pneumatically connecting the sections of said chest, a valve-box associated with one of the sections of said chest and removable therewith, a detachable windway between said action pneumatics and said valve-box, a second valve-box associated with another of the sections of said chest and removable therewith, a second detachable windway between the sheet-propelling mechanism and said second valve-box, a valve in each of said valve-boxes and disconnectible valve-operating mechanism connected with said valves, part of said valve-operating mechanism when disconnected being removable with one or another of the sections of said chest.
18. In mechanism for mechanically playing a musical instrument, a casing, sheet-propelling mechanism supported within said casing, a chest composed of a plurality of separately removable sections removably secured within said casing, wind-supplying apparatus distributed upon and communicating with the sections of said chest, a windway communicating with said sheet-propelling mechanism and detachably connected with one of the sections of said chest, disconnectible or severable means pneumatically connecting the sections of said chest, and mechanism operatively connected with said wind-supplying apparatus, said mechanism being independently detachable from the wind-supplying apparatus of the separate sections of said chest.
19. In mechanism for mechanically playing a musical instrument, a casing, action pneumatics supported within said casing, a chest composed of a plurality of separately removable sections removably secured within said casing, wind-supplying apparatus distributed upon and communicating with the sections of said chest, a windway communicating with said action pneumatics and detachably connected with one of the sections of said chest, disconnectible or severable

means pneumatically connecting the sections of said chest, and mechanism operatively connected with said wind-supplying apparatus, said mechanism being independently detachable from the wind-supplying apparatus of the separate sections of said chest.

20. In mechanism for mechanically playing a musical instrument, action pneumatics, a chest provided with wind-supplying apparatus and composed of a plurality of separately removable sections, means for removably securing the separate sections of said chest, disconnectible or severable means pneumatically connecting the sections of said chest, and a detachable windway between said action pneumatics and one of the sections of said chest.

21. In mechanism for mechanically playing a musical instrument, sheet-propelling mechanism, a chest provided with wind-supplying apparatus and composed of a plurality of separately removable sections, means for removably securing the separate sections of said chest, disconnectible or severable means pneumatically connecting the sections of said chest, and a detachable windway between said sheet-propelling mechanism and one of the sections of said chest.

22. The combination in an automatically operated musical instrument, of pneumatically operated mechanism, a movable element acting to cause the operation of the instrument, mechanism for controlling the movement of said movable element, and means whereby the condition of pneumatic pressure in said pneumatically operated mechanism automatically affects said controlling mechanism to determine the direction of movement of said movable element.

23. The combination in an automatically operated musical instrument, of pneumatically operated playing mechanism, a movable member acting to cause operation of said playing mechanism, and means for advancing and returning said member, said means being controlled by the pneumatic condition in said playing mechanism to advance and return said member.

24. In an automatic musical instrument, the combination of pneumatically operated mechanism, and mechanism whereby a movable element acting to cause the operation of said mechanism is automatically advanced when the pneumatic condition in said mechanism is adapted for the operation of the same and is automatically returned when said pneumatic condition is not adapted for the operation of said mechanism.

25. In an automatical musical instrument, the combination of pneumatically operated playing mechanism, a driving motor, mechanism for advancing and returning a movable element acting to cause the playing of the instrument, and means whereby said advancing and returning mechanism is actuated by

changes in the pneumatic condition in said playing mechanism.

26. In an automatic musical instrument, the combination of pneumatically operated playing mechanism, a driving motor, mechanism whereby said motor can be caused to advance and return, a movable element regulating the playing mechanism, and means whereby said advancing and returning mechanism is automatically operated in one direction or the other, depending on the condition of pneumatic pressure in the playing mechanism.

27. In an automatic musical instrument, the combination of pneumatically operated playing mechanism, a driving motor, means whereby a traveling music sheet may be advanced and rewound through the instrumentality of said motor, and means whereby said advancing and rewinding means may be controlled to cause the motor to advance the music sheet when the condition of pneumatic pressure in the playing mechanism is such as to permit playing and rewind said sheet when the condition of said pneumatic pressure is such as to prevent playing by said playing mechanism.

28. The combination with a pneumatically operated playing mechanism, mechanism for advancing and rewinding a traveling music sheet, a motor for actuating said advancing and rewinding mechanism, a pneumatic connected with the playing mechanism so as to be controlled by the condition of pneumatic pressure in said playing mechanism and means whereby said pneumatic determines the application of the power of said motor to the advancing and rewinding mechanism.

29. The combination of pneumatically operated playing mechanism, advancing and rewinding mechanism, a motor for actuating said advancing and rewinding mechanism, a pneumatic connected with said playing mechanism so as to be controlled by the pneumatic pressure of said playing mechanism, and connections between said pneumatic and said advancing and rewinding mechanism whereby the latter is actuated in an advancing manner when the pneumatic pressure of the playing mechanism is such as to effect operation of the playing mechanism and to bring about a rewinding action when said pneumatic pressure is such as not to effect operation of said playing mechanism.

30. The combination of pneumatically operated playing mechanism, means for advancing and rewinding a traveling music sheet, said means including a clutch, and a pneumatic connected with said clutch for operating the same and also connected with said playing mechanism so as to be controlled by the pneumatic pressure of the same.

31. The combination with a pneumatic ac- 130

- tion, of means for advancing and rewinding a traveling music sheet, said means including a clutch, and a pneumatic connected with said clutch so as to cause the same to connect the advancing and rewinding means for advancing action when said pneumatic is collapsed and to cause connection for rewinding when said pneumatic is expanded, said pneumatic being also connected with the pneumatic action so as to be collapsed when the air pressure in the action is reduced for playing and to be expanded when the reduced air pressure is off from said action.
32. The combination of pneumatically operated playing mechanism, means for advancing and rewinding a traveling music sheet, and means controlled by the pneumatic tension in the playing mechanism for affecting the action of the advancing and rewinding means.
33. The combination of pneumatically op-

erated playing mechanism, a music sheet propelling motor, and means controlled by the pneumatic pressure effective upon the playing mechanism for varying the operation of the motor.

34. The combination of action pneumatics, exhaust devices adapted to create pneumatic tension, action windways connecting said exhaust devices and said action pneumatics, movable gearing mechanism, and a shifting pneumatic communicating with said action windways adapted to shift said movable gearing mechanism in reverse directions on alternate application and withdrawal of tension in said windways.

In testimony whereof I hereunto affix my signature in presence of two witnesses.

PAUL BROWN KLUGH.

Corrections in Letters Patent No. 1,172,805.

It is hereby certified that in Letters Patent No. 1,172,805, granted February 22, 1916, upon the application of Paul Brown Klugh, of Chicago, Illinois, for an improvement in "Musical-Instrument Players," errors appear in the printed specification requiring correction as follows: Page 7, line 112, claim 9, cancel the word "and"; same page, line, and claim, after the word "windways" insert the word *and*; page 9, line 72, claim 26, after the word "return" cancel the comma; and that the said Letters Patent should be read with these corrections therein that the same may conform to the record of the case in the Patent Office.

Signed and sealed this 18th day of April, A. D., 1916.

[SEAL.]

Cl. 84—161.

R. F. WHITEHEAD,

Acting Commissioner of Patents.
